UNITED STATES PATENT OFFICE.

FLORENCE C. BIGGERT, JR., OF CRAFTON, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

MILL.

Application filed June 10, 1922. Serial No. 567,281.

To all whom it may concern:

Be it known that I, FLORENCE C. BIGGERT, Jr., a citizen of the United States, residing at Crafton, in the county of Allegheny and 5 State of Pennsylvania, have invented a new and useful Improvement in Mills, of which the following is a full, clear, and exact description.

My invention relates to mills and is applicable to any kind of mill having smooth 10 rolls and to mills having certain forms of shaping rolls.

My invention relates particularly to a method of and means for hydraulically 15 supporting, cooling, lubricating and reinforcing the rolls of mills, and will be better understood by reading the following description taken in connection with the accompanying drawings illustrating one embodiment of my invention, and in which:

Figure 1 is a front elevation of a part of a mill embodying my invention;

Figure 2 is a section on line II—II of Figure 1;

Figure 3 is a top plan view of the cylinder and piston;

Figure 4 is a bottom plan view of the piston, and

Figure 5 is a partial side elevation of the mill shown in Figures 1 and 2.

Referring to the drawings, the mill comprises the usual housings 1 and 2 for the rolls and carries the bearings 3, 4, 5 and 6 in which the rolls are mounted. The bearings 4 and 5 are held in place by the screws 30

7 and 8, respectively. The parts so far described may be of any well known or desired construction. Mounted between and carried by the housings 1 and 2 are two 35

cylinders 9 and 10. These cylinders are provided with pistons 11 and 12, respectively. The piston 11 engages the roll 13 and the piston 12 engages the roll 14. The pistons 11 and 12 are provided with chambers 40

15 and 16, respectively, which communicate through the passages 17 and 18 with the interior portions 19 and 20 of the cylinders 9 and 10. Any suitable packing material 45

21 may be placed around the pistons 11 and 12. The lower portions of the pistons are shaped to closely fit the surface of the rolls as shown in Figure 2 so that each of the chambers 15 and 16 has one side constituted by the rolls 13 and 14, respectively. The pipes 22 and 23 communicate with fluid 50 under pressure and conduct the same into the chambers 19 and 20 and from these chambers into the chambers 15 and 16 through the passages 17 and 18. The areas of the pistons 11 and 12 which are subjected to the pressures in the chambers 19 and 20 are larger than the areas of the chambers 15 and 16. These areas are so designed relative to each other that sufficient pressure will be created between the edges 24 and 25 55 of the piston 11 and the edges 26 and 27 of the piston 12 and the rolls 13 and 14, respectively, to form a fairly tight joint so that sufficient pressure may be produced upon the fluid in the chambers 15 and 16 60 to reinforce the rolls substantially throughout their length. The pressure created in the chambers 15 and 16 directly upon the rolls 13 and 14 also act to relieve the necks 65 of the rolls of considerable pressure. The contact of the fluid in these chambers with the rolls and the escape of a relatively small amount of fluid between the rolls and the edges of the chambers act to effectively cool 70 the rolls and to reduce the metallic friction 75 between the rolls and the edges of the chambers or pistons by creating a sheet of fluid between the rolls and the edges of the pistons.

In mills of this character the lower rolls 80 are usually fixed and springs or similar means are used to maintain the rolls separated when no work is in the mill. In my mill the lower roll is fixed and supported by its bearings. Means are provided for 85 adjusting the upper roll to accommodate materials of different thicknesses. These means comprise screws 7 and 8 and wedges 28 and 29 which wedges may be moved in either direction by bolts 30 and 31. The 90 wedges act to raise the upper roll against the points of the screws 7 and 8 when said screws have been adjusted to accommodate 95

the thickness of the material being rolled. Two wedges are provided for each end of the rolls.

The wedges act to hold the upper roll substantially against the points of the screws 7 and 8 when no work is in the mill. This or similar means is particularly efficacious in my device wherein the upper roll is reinforced and supported by the means here-
10 tofore described.

By reason of the floating nature of the pistons 11 and 12 the adjustment of the upper roll does not in any way adversely affect the fluid action on the rolls.

15 When there is no work in the mill the pressure may be cut off from the cylinders 9 and 10. If it is not cut off the wedges 28 and 29 will act to maintain the rolls in the adjusted position so that the upper roll 20 is against or substantially against the points of the screws 7 and 8. If the pressure should be kept in cylinder 10 and cut off from cylinder 9 the positions of the rolls relative to each other would not be changed.
25 From the foregoing it will be seen that means are provided for positively holding the rolls fixed relative to each other.

30 My invention has many advantages, among which may be mentioned that rolls of smaller diameter may be used when my invention is employed and by reason of the reinforcing action the rolls are effectively prevented from springing; by the use of smaller rolls, less power is required to drive 35 the mill and many advantages are secured as is well known in the art; the medium which acts to reinforce the rolls also supports the same to a large extent and also acts to cool the rolls and to lubricate the same by 40 reducing the friction between the pistons and the rolls; by properly proportioning the relation of the areas of the pistons the required amount of pressure may be created between the edges of the pistons and the 45 rolls to effectively seal the chambers in which the reinforcing and cooling fluid is confined.

Many other advantages will be apparent to those skilled in the art and need not be 50 recited here.

While I have shown and described one embodiment of my invention, I desire it to be understood that I am not limited to the exact arrangement shown and described, as 55 many changes may be made in the details thereof without departing from the spirit of my invention.

I claim:

60 1. In a mill, the combination of a pair of coating rolls, and a differential area piston having a common pressure supply for both ends of the piston for maintaining fluid pressure on one side of one of said rolls.

65 2. In a mill, the combination of a pair of coating rolls, and a differential area piston

having a common pressure supply for both ends of the piston for maintaining fluid pressure along one side of one of said rolls and substantially throughout the length thereof.

3. In a mill, the combination of a pair of coating rolls, means for positively spacing said rolls, means for reinforcing one of said rolls comprising a member engaging the roll and having a fluid chamber adjacent the 75 roll, and means for supplying fluid under pressure to said chamber.

4. In a mill, the combination of a pair of coating rolls, means for positively spacing said rolls, a piston engaging one of said rolls and a fluid chamber in said piston, one side of said chamber being constituted by 80 one of said rolls.

5. In a mill, the combination of a pair of coating rolls, a piston engaging one of said rolls and a fluid chamber in said piston there being a communicating passage from end to end of said piston, one side of said chamber being constituted by one of said rolls and means for holding the piston against the roll 85 and supplying fluid to said chamber through said passage.

6. In a mill, the combination of a pair of coating rolls, journals for said rolls, fluid means for reinforcing said rolls intermediate the journals, and means for holding said rolls positively spaced.

7. In a mill, the combination of a pair of coating rolls, journals for said rolls, and floating means above and below the roll pass 100 for creating a fluid pressure directly on both of said rolls intermediate the journals.

8. In a mill, the combination of a pair of coating rolls, journals for said rolls, a cylinder, a differential area fluid piston in said cylinder for reinforcing one of said rolls, said piston having a chamber adjacent the roll connected to the interior of said cylinder, and means for creating a fluid pressure 105 directly on said roll.

9. In a mill, the combination of a roll, a cylinder, a piston in said cylinder engaging said roll and having a chamber therein adjacent the roll, said cylinder and said chamber being interconnected, and means for supplying fluid under pressure for holding the piston against the roll and creating fluid pressure directly upon the roll to reinforce and cool the roll.

10. In a mill, the combination with one of the rolls of the mill, of a cylinder, a piston therein having a chamber, one side of which is constituted by the roll, means connecting said chamber to the interior of said cylinder, the areas of said piston and chamber being such that the resultant hydraulic pressure acts to operatively seal the chamber against the roll whereby the liquid in the chamber supports and reinforces the roll.

11. In a mill, the combination with one of the rolls of the mill, of a cylinder, a piston therein having a chamber, one side of which is constituted by the roll, means for supplying liquid under pressure to the cylinder and the chamber in the piston, the areas of the piston and the chamber being so proportioned that the liquid in the cylinder acts to operatively seal the chamber against the roll and the liquid in the chamber acts to cool, support and reinforce the roll.
- In testimony whereof I have hereunto set my hand.

FLORENCE C. BIGGERT, JR.
